REFRIGERATOR BREAKER STRIP
CONSTRUCTION

Earl D. Drake, Greenville, Mich., assignor to Gibson Refrigerator Company, Greenville, Mich., a corporation of Michigan

Application January 13, 1944, Serial No. 518,051

4 Claims. (Cl. 220—9)

1

This invention relates to refrigerators of the household type, and more particularly to the cabinets thereof.

The principal object of the invention is to provide a refrigerator cabinet of relatively inexpensive, light, but particularly rugged construction.

Another object is to provide a refrigerator cabinet in which reinforcing means is provided about the front of the cabinet shell and about the access opening to the liner, and the reinforcing means are rigidly interconnected so that the liner and shell mutually stiffen each other.

A further object of the invention is to provide a cabinet having a novel form of support for the liner within the outer shell.

A still further object is to provide a refrigerator cabinet in which the joints between the various sections of the walls are effectively concealed.

Another object is to provide an efficient seal about the door opening designed to reduce the space between the refrigerator door and cabinet to a minimum.

A still further object is to provide a refrigerator cabinet having a breaker strip and gasket mounted on the front thereof, and in which the breaker strip and gasket form substantially the entire exposed front face of the cabinet.

A still further object of the invention is to provide a novel means for connecting the breaker strips to the outer shell and liner of the cabinet.

These objects will more fully appear in the following specification when read in connection with the accompanying drawings, wherein:

Figure 1 is a front elevational view of a refrigerator cabinet embodying the present invention;

Figure 2 is a cross-sectional view taken on substantially the line 2—2 of Figure 1;

Figure 3 is a fragmentary cross-sectional view on an enlarged scale taken on substantially the line 3—3 of Figure 1;

Figure 4 is a fragmentary cross-sectional view taken on substantially the line 4—4 of Figure 1;

Figure 5 is a front elevational view of the refrigerator cabinet with the ornamental breaker strips between the liner and outer shell removed in order to show the interior construction of the cabinet;

2

Figure 6 is a fragmentary cross-sectional view taken on substantially the line 6—6 of Figure 5;

Figure 7 is an isometric view of the cabinet liner;

5 Figures 8 to 10 are fragmentary cross-sectional views taken on substantially the lines 8—8, 9—9 and 10—10, respectively, in Figure 5;

Figure 11 is a fragmentary cross-sectional view showing a modified form of the means for sealing the space between the cabinet and door;

10 Figure 12 is a cross-sectional view of a still further modified form of sealing means;

Figure 13 is a fragmentary vertical sectional view of a modified form of refrigerator cabinet;

15 Figure 14 is a cross-sectional view taken on substantially the line 14—14 of Figure 13; and

Figure 15 is a fragmentary cross-sectional view taken on substantially the line 15—15 of Figure 13.

20 In the drawings, Figures 1 to 10 illustrate one form of the present invention. The figures show a refrigerator cabinet 10 formed to provide a refrigerated food storage compartment 11 in the upper part thereof and a machinery compartment

25 12 in the lower part thereof. In general, the cabinet comprises an outer shell 13 and a liner 14 supported within the outer shell and spaced therefrom. The liner 14 defines all but the front walls of the food storage compartment 11. Insulating material 9 is packed between the liner and shell.

The outer shell is made up of a so-called wrap around side panel 15, a back panel 16, and a base 17. Preferably the wrap around side panel 15 is

35 formed from one piece of sheet metal bent into U shape, as shown particularly in Figure 5. The front edge of the side panel 15 is provided with reinforcing means in the form of a generally U-shaped channel 18 and a laterally inwardly extending flange 19.

40 The channel and flange are formed by bending the metal of the side panel 15 inwardly, then rearwardly upon itself, and finally laterally inwardly to form the flange 19. See particularly Figure 10.

45 The rear edge of the side panel 15 is bent laterally inwardly to provide a flange 20 to which the back panel 16 is welded or otherwise secured, as shown in Figures 2, 4 and 6. The back panel 13 is formed with an opening at the lower end

50 thereof defined by an inwardly extending flange

21. The opening just mentioned is at the rear of the machinery compartment 12.

The lower ends of the wrap around side panel 15 and the back panel 16 are tied together by the base 17 which is welded or otherwise secured thereto.

A front cross rail 7 is connected to the front edges of the side panel 15 between the machinery compartment 12 and the food storage compartment 11. A metal pan 8 forms the roof of the machinery compartment 12. The pan 8 rests on the lower flange of cross rail 7 and flange 21 on the back panel 16 and forms a support for insulation 9.

The liner 14 is preferably of generally rectangular box shaped configuration. (See Figure 7 particularly.) It is provided with an access opening at the front thereof. Preferably the liner is formed from three pieces of sheet metal. The back 22 and two upright sides 23 of the liner are formed from one piece of metal bent into U shape, as shown in Figure 2. The forward extremities of the sides of the liner are reinforced by bending the metal laterally outwardly, thence rearwardly to form vertically extending channels 24, and then laterally outwardly to provide flanges 25, see Figures 7 and 10.

The top 26, and bottom 27 of the liner are identical and are formed from flat sheets of metal. The portions at the front edges of the top 26 and bottom 27 are reinforced by bending the metal outwardly and rearwardly to provide channels 28, and then outwardly again to provide flanges 29. The top 26 and bottom 27 of the liner overlie the top and bottom edges of the back 22 and the sides 23. (See Fig. 7.) The channels 28 extend laterally beyond the side 23 to overlie the upper and lower ends of the channels 24 on the sides of the liner. Preferably the edges of the various walls of the liner are seam welded together and the top 26 and bottom 27 are welded to the upper and lower ends of channels 28 and flanges 29. Thus, it will be seen that the perimeter of the access opening at the front of the liner is defined by a reinforcement of angular cross section extending entirely around the opening, and formed by channels 24 and 28 and flanges 25 and 29. This provides an extremely rigid construction, one that maintains its rectangular configuration even if made of relatively light gauge material.

The liner is supported upon the outer shell by means of two relatively heavy horizontal channel shaped cross members 30 and 31. Preferably the flanges of the channels extend forwardly from the web thereof. Cross member 30 embraces the flange 29 on the top of the liner. The upper side wall of the channel shaped reinforcement 28 rests on the lower flange of cross member 30.

The cross member 31 embraces the flange 29 on the bottom 27 of the liner and the lower edge of flange 29 preferably rests on the lower flange of the cross member 31. The web of the cross member 31 and flange 29 of bottom 27 of the liner are bolted together in the same manner as the upper cross member 30 and flange 29 are connected together.

The ends of the two cross members 30 and 31 are positioned behind the flange 19 on the outer shell, as indicated in Figures 5 and 9. The cross members are supported from the flange 19 by bolts or screws 32. The cross members 30 and 31 are spaced from the flange 19 by bushings 33 of rubber or other insulating material. The bushings 33 insulate the liner and cross members 30

and 31 from the outer shell so that no appreciable heat loss occurs.

The liner and outer shell are additionally braced by four plates of plywood or similar non-heat conducting material 34 which are bolted to the flanges 19 and 25 at approximately the midpoint of each side of the cabinet. See Figure 5. The plywood plate 34 at one side of the cabinet provides support for the latch of the door. The plates 34 provide some slight support for the cabinet within the outer shell but are primarily intended to act as additional stiffening means for the four sides of the liner and outer shell.

The front of the cabinet proper around the access opening in the liner is formed by ornamental breaker strips 35. The breaker strips may be formed from any suitable hard insulating material, ornamented as desired. The cross section of each breaker strip is illustrated in Figure 3. The laterally outer edge of each breaker strip is provided with an inturned portion 36 paralleling the side panel 15 of the outer shell which terminates in a laterally outwardly extending flange 37. The flange 37 is parallel to and overlies the corresponding flange 19 on the outer shell. The portion 36 of each breaker strip is spaced away from the adjoining side wall of the channel 18 to form a forwardly opening recess 38. The recess 38 is adapted to receive a gasket or sealing strip 39 of soft rubber or similar material, which will be more fully described presently.

The breaker strips 35 are connected to the cabinet by resilient fasteners 40 and 41. Fasteners 40 are in the form of narrow spring metal strips attached to the breaker strips 35 at 42 in any suitable manner. The rearward ends of the strips 40 are provided with hook shaped members 43 which snap over the adjacent edges of the flanges 25 on the liner. The flanges 37 of the breaker strips 35 are connected to the flange 19 on the side wall 15 by wire fasteners 41 shaped to the configuration shown in Figure 3. The fasteners are pushed through corresponding openings in the flanges 19 and 37 and snap into place to hold the flanges together.

The sealing gasket 39 is an elongated tube formed to the configuration shown in Figure 3. Opposite side walls of the gasket are parallel for a portion of their width and engage the sides of the recess 38. The base of the gasket 39 is provided with grooves extending lengthwise thereof which receive opposite sides of the spring metal fasteners 41 to hold the gasket 39 in place. The manner of attachment will be obvious from an inspection of Figure 3.

The front wall of the gasket 39 is bowed forwardly to a slight extent, but it does not extend much beyond the front face of the cabinet 10, as defined by the breaker strips. The front wall of the gasket 39 is engaged by a plastic or metal bead 44 secured to the perimeter of the door 45. The bead 44 is of convex form so that only a very narrow part thereof engages the gasket 39 more or less is the manner of a knife edge, so that when the door is closed the front wall of the gasket is sprung rearwardly and to some extent embraces the bead 44. That engagement provides a particularly effective seal between the door and the cabinet. It will be noted that if desired the bead 44 can be made very thin, and as the gasket 39 is practically wholly embedded in the front of the cabinet, the space between the door and cabinet can be made very small. At the same time the gasket 39 can be made relatively thick in a fore and aft direction, so as to

obtain the necessary great resilience required to provide an effective seal. The gasket is supported laterally by the side walls of the recesses 38 so that no matter where the strips 44 engage the gaskets a tight seal will be effected. Furthermore, the gasket overlies and conceals the joint between the breaker strips and the panel 15. It will be noted that the breaker strips and the gasket form substantially the entire exposed front face of the cabinet, except for the front wall of channel 18 and a very narrow strip about the access opening in the liner.

Because of the peculiar configuration of the foremost portions of the liner 14 and the side panel 15 of the outer shell, a particularly sturdy cabinet may be formed from relatively thin sheet metal. The rectangular configuration of the front portion of the liner, reinforced as it is by the channels 24 and flanges 25, is not easily distorted. That is, it is not easily forced out of its rectangular shape. The cross members 30 and 31 being connected to the upper and lower ends of this rigid rectangle at a plurality of points will transmit from one to the other any stresses imposed upon the outer shell or the liner. The liner then becomes an effective brace for the entire outer shell, and the outer shell with its reinforcement about its top and side edges acts to stiffen the liner.

In addition, the reinforcing channels 18 and flanges 19 on the outer shell act as pillars to provide a sturdy support for the liner upon the outer shell. Thus, it is unnecessary to support the liner at the back or at the bottom, as has been the custom heretofore.

Figure 11 discloses a somewhat modified form of fastening means for the adjacent edges of the breaker strip and outer shell. In Figure 11 the breaker strip is designated by the numeral 50. It has a laterally extending flange 51. The side panel of the outer shell is designated by the numeral 52. The side panel 52 is provided with a rearwardly extending channel 53 and a laterally forwardly extending flange 54. The flanges 51 and 54 are fastened together by screws 55 which hold in place within the recess U-shaped clips 56. The clips 56 embrace the base of a gasket 57 similar to gasket 39.

A door 58 has secured thereto C-shaped clips 59 over which a resilient bead 60 is snapped. The portion of the bead 60 remote from the door engages the front surface of the gasket 57 in the same manner as strip 44 previously described.

Figure 12 shows a still further modified form a sealing device for the space between the door and the cabinet. A breaker strip 61 having a flange 62 is connected to a side panel 63 provided with a flange 64 by means of screws 65. The adjacent portions of the breaker strip 61 and side wall 63 provide a recess 66 into which a gasket 67 is inserted. Tongues 68 and 69 are struck inwardly from the respective sides of the recess 66 to support the rubber gasket 67. A bead 70 is connected to a door 71. The bead 70 engages the front wall of the gasket 67 to form a seal between the door and cabinet in the same manner as the previously described form of the invention.

Figures 13 to 15 show a modified form of refrigerator cabinet. This cabinet differs from the cabinet shown in Figures 1 to 10 primarily in the fact that the forward portion of the liner extends forwardly beyond the front of the outer shell so that more space within the cabinet may be provided when a door having a hollowed inner face is used.

The cabinet comprises an outer shell 80 of exactly the same configuration as the shell previously described. The outer shell has a rearwardly opening reinforcing channel 81 about its front perimeter and a laterally inwardly extending flange 82.

10 A liner 83, which is of the same configuration as liner 14, is also employed. The liner is provided with a rearwardly opening channel shaped reinforcement 84 about the perimeter of the access opening at the front and is provided with laterally extending flanges 85.

15 The liner is supported upon the outer shell 80 by upper and lower cross members 86 and 87 respectively of channel shaped cross section. The cross members, instead of being straight, as in the previous device, are bent rearwardly at their extremities. See Figure 15. Thus, when the ends of the cross members 86 and 87 are connected to the flanges 82 the central portions of the cross members which support the liner project forwardly to some extent. That puts the front portion of the liner forwardly of the front portion of the outer shell.

20 25 The liner and shell are connected intermediate the extremities of each side wall by plates 88 of plywood or similar material formed to the S-shaped configuration shown in Figure 13. A plurality of breaker strips 89 connect the flanges 82 and 85 of the various shell and liner and conceal the joints between the various members. Concealing gaskets 90 are attached to the cabinet in the same manner as in the modification previously described.

30 35 The reason for the particular construction shown in Figures 13 to 15 is apparent from an inspection of Figure 14. A door 91 having an arcuate liner wall 92 is employed. The inner wall is curved in the manner disclosed in order 40 to provide somewhat more space within the refrigerator cabinet than would be obtained if the inner panel were flat. In order to utilize that space the shelves indicated at 93 should extend into the arcuate space in the door. That necessitates the extension of the liner forwardly in order to aid in effectuating a proper seal between the door and cabinet, as well as to provide better support for the shelves 93.

45 It will be noted that the modification shown in Figures 13 to 15 differs from the previously 50 described form of the invention only in the shape of the various parts connecting the liner to the shell. The shape of the front face of the cabinet around the door is determined substantially entirely by the shape of the breaker strip 89 and gasket 90. Hence the design of the front face of the cabinet can be varied throughout a wide range merely by changing the relative positions of the liner and shell and varying the shape of the breaker strip, or breaker strip and gasket.

60 It will be apparent from the foregoing that this invention provides primarily a particularly rugged refrigerator cabinet. The reinforcing means about the front perimeters of the outer shell and liner stiffen the shell and the liner, and due to the particular connection of the liner to the outer shell, the liner and shell mutually reinforce each other. Thus, there is no tendency for the cabinet to tend to lean sideways, or in 65 other words, assume a shape other than rectangular. In addition, the breaker strips overlie practically the entire front portions of the refrigerator cabinet and the only unsightly joints between the various parts are completely concealed by the sealing gaskets which lie within the 70 75

recesses formed therefor. Furthermore, the placement of the gaskets within the aforesaid recesses permits the use of a relatively large gasket with its attendant resiliency, and thereby provides a more effective seal without making the space between the cabinet and door unduly large. 5

The scope of the invention is indicated in the appended claims.

I claim:

1. A refrigerator cabinet including a side wall 10 comprising spaced apart inner and outer panels, said outer panel having a portion at its front edge reversely bent rearwardly and terminating in a laterally extending flange, a breaker strip having a portion adjacent said outer panel extending rearwardly and provided with a laterally extending flange overlapping said first named flange to form a forwardly opening recess, means connecting the other edge of said breaker strip to said inner panel, a resilient sealing gasket in 20 said recess, and resilient means holding said gasket in said recess and extending through said flanges to attach said flanges together.

2. A refrigerator cabinet including a side wall comprising spaced apart inner and outer panels, said outer panel having a portion at its front edge reversely bent rearwardly and terminating in a laterally extending flange, a relatively thin rigid insulating sheet material breaker strip having a portion adjacent said outer panel extending rearwardly and terminating in a lateral flange overlapping said first named flange whereby to form a forwardly opening recess, means connecting the other edge of said breaker strip to said inner panel, and a resilient sealing gasket 35 in said recess.

3. A refrigerator cabinet including a side wall comprising spaced apart inner and outer panels, said outer panel having a portion at its front edge reversely bent rearwardly and terminating in a laterally extending flange, a relatively thin rigid insulating sheet material breaker strip having a portion adjacent said outer panel extending rearwardly and terminating in a lateral flange overlapping said first named flange where- 45

by to form a forwardly opening recess, means connecting the other edge of said breaker strip to said inner panel, and strip means in said recess concealing the same.

4. A refrigerator cabinet including a side wall comprising spaced apart inner and outer panels, said outer panel having a portion at its front edge reversely bent rearwardly and terminating in a laterally extending flange, a relatively thin rigid insulating sheet material breaker strip having a portion adjacent said outer panel extending rearwardly and terminating in a lateral flange overlapping said first named flange whereby to form a forwardly opening recess adapted to receive a sealing gasket, and means connecting the other edge of said breaker strip to said inner panel.

EARL D. DRAKE.
